UNITED STATES PATENT OFFICE.

THOMAS H. RADCLIFFE, OF BROOKLYN, NEW YORK.

BALL-COCK.

1,142,620.

Specification of Letters Patent. Patented June 8, 1915.

Application filed December 6, 1913. Serial No. 805,133.

To all whom it may concern:

Be it known that I, THOMAS H. RADCLIFFE, a citizen of the United States, residing at Brooklyn, in the county of Kings and State of New York, have invented certain new and useful Improvements in Ball-Cocks, of which the following is a specification, reference being had to the accompanying drawings.

This invention relates to certain improvements in ball-cocks and has relation more particularly to a device of this general character especially designed and adapted for use in connection with flushing tanks and an object of the invention is to provide a novel and improved ball-cock so arranged and constructed as to increase the efficiency and durability of the device and to permit of the ready and convenient removal and replacement of any of the parts which are liable to wear or which require to be renewed.

The invention also has for an object to provide a device of this general character having novel and improved means whereby the rod and float are prevented from falling too low within the tank, whereby it is assured that the ball-cock is maintained open under full pressure until the tank is almost full.

The invention also has for an object to provide a novel and improved device of this general character wherein the refilling tube is adapted to be connected therewith in close proximity to the valve proper whereby a requisite flow through the refilling tube is assured throughout substantially the entire period of refilling the tank.

The invention also consists in the details of construction and in the combination and arrangement of the several parts whereby certain important advantages are attained and the device is rendered simpler, less expensive and otherwise more convenient and advantageous for use all as will be herein-after more fully set forth.

The novel features of the invention will be carefully defined in the appended claim.

In order that my invention may be better understood, I will now proceed to describe the same with reference to the accompanying drawings, wherein—

Figure 1 is a longitudinal sectional view taken through a ball cock constructed in accordance with my invention; Fig. 2 is a bottom plan view of the device as shown in

Fig. 1; Fig. 3 is a view similar to Fig. 2, with parts shown in section; and Fig. 4 is a view in elevation of the valve mechanism proper, as comprised in the present embodiment of my invention.

As disclosed in the accompanying drawings, 1 denotes a casting of suitable dimensions having disposed longitudinally thereof the conduit 2 communicating at one end with the tubular depending nipple or connection 3 having its lower end portion inferiorly threaded, as at 4, whereby a proper union with a supply pipe may be effected with convenience. The opposite extremity 65 of the conduit 2 is in communication with the depending nipple 5 having its inner end reduced, as at 6, the under surface of such reduced portion immediately adjacent the opening 7 therethrough being provided with the annular depending flange 8, whereby a valve seat is afforded, with which is adapted to coat the valve 9 carried by the rod 10 projecting through the sleeve 11 in threaded engagement with the nipple 5. Intermediate 80 the nipples 3 and 5 the casting is provided with the depending nipple 12 in communication with the nipple 5 adjacent the inner end thereof through the medium of the by-pass 14, the lower extremity of such 85 intermediate nipple 12 being herein shown as screw-threaded, as at 15, to afford requisite connection or coupling with a suitable discharge pipe through which the fluid passing through the cock is adapted to be delivered within the receptacle or tank (not shown).

From the foregoing description, it will be observed that the fluid before entering the tank or receptacle passes through the nipple 3, the conduit 2 into the nipple 5 through the by-pass 14 and through the intermediate nipple 12, such flow through the casting 1 95 being under control of the valve 9, as is believed to be self-evident.

The lower or free end portion of the valve stem 10 is provided with an elongated longitudinally directed slot 16 through which is adapted to pass the operating lever 17, one end of which being pivotally supported, as 105 at 18, between the spaced ears 19 projecting or depending from the outer end of the sleeve 11, while the opposite extremity of such lever 17 is formed to afford a socket member 20, whereby suitable connection 110 may be had with a suitable rod or stem (not shown), to the outer or opposite end of

which a conventional ball or float is adapted to be connected.

Intermediate its length, the sleeve 11 is provided with the annular flange 21 which is adapted to contact with the free extremity of the nipple 5, and it is to be observed that the direction in which the lever 17 may extend relatively to the casting may be determined by interposing between such annular flange 21 and the adjacent extremity of the nipple 5 a washer 22 of requisite thickness, the thickness of such washer, as is believed to be clearly apparent, determining the adjustment of the lever. It is also to be observed that a comparatively short stroke of the rod 10 is required to seat or unseat the valve 9. By this arrangement it is thought to be obvious that the valve is open for the flow of the fluid therethrough under full pressure until the tank is substantially entirely refilled.

In order to afford a proper connection for a conventional refilling tube (not shown), I have in communication with the nipple 5 the laterally directed nipple 23, whereby a convenient connection with a refilling tube may be effected and by having this nipple 23 positioned as herein set forth, it will be observed that a flow of fluid through the refilling tube will occur throughout the period the valve 9 is in open adjustment.

From the foregoing description, it is thought to be obvious that a ball-cock constructed in accordance with my invention is of an extremely simple and comparatively

inexpensive nature and is particularly well adapted for use by reason of the convenience and facility with which it may be assembled and the efficiency with which it performs its functions and it will also be obvious that my invention is susceptible of some change and modification without material departure from the principles and spirit thereof and for this reason I do not wish to be understood as limiting myself to the precise arrangement and formation of the several parts herein shown in carrying out my invention in practice. 40 45

Having thus fully described my invention what I desire to claim and secure by Letters Patent, is:

In a device of the class described, a casting comprising a chamber and three integral depending nipples communicating with the chamber and adjacent to one another, 55 the first nipple adapted for connection with a supply pipe, the second nipple adapted for connection with a discharge pipe and communicating with the chamber through a by-pass, an integral valve seat between the chamber and by-pass, and valve mechanism in the third nipple and co-operating with the seat for controlling the passage of fluid from the chamber to the by-pass. 60

In testimony whereof I hereunto affix my signature in the presence of two witnesses.

THOMAS H. RADCLIFFE.
